HEAD FOR A HAND VACUUM CLEANER

Medard W. Welch and John Dubrovin, Chicago, Ill.

Application March 20, 1957, Serial No. 45,354

Term of patent 14 years

(Cl. D9—2)

Fig. 1 is a side elevational view of a head for a hand vacuum cleaner, showing our new design;

Fig. 2 is an elevational view thereof as viewed from the left of Fig. 1; and

Fig. 3 is a top plan view thereof.

The broken line showing in Fig. 1 is for illustrative purposes only.

We claim:

The ornamental design for a head for a hand vacuum cleaner, as shown and described.
